UNITED STATES PATENT OFFICE.

FRANK E. MILLER, OF NEW YORK, N. Y.

EAR-PROTECTOR.

1,305,828.

Specification of Letters Patent. Patented June 3, 1919.

Application filed April 24, 1918. Serial No. 230,422.

To all whom it may concern:

Be it known that I, FRANK E. MILLER, a citizen of the United States, and a resident of New York city, county and State 5 of New York, have invented a certain new and useful Ear-Protector, set forth in the following specification.

My invention relates to the protection of the human ear. In heavy artillery practice, the ear drums of the gunners are always 10 endangered. To understand the reason for the large number of fractured ear drums suffered by those in the neighborhood of detonations, it should be borne in mind that 15 the human tympanum or ear drum, in addition to its auditory functioning, constitutes a physical partition between the cavity of the outer ear, known as the external meatus, and the tympanic cavity. The tympanic cavity is substantially completely 20 inclosed, although it is connected, by a small tubular duct, known as the Eustachian tube, with the mouth cavity. This tube, in its pneumatic functioning, is intended to effect 25 a balance in air pressure between the external meatus and the tympanic cavity. This functioning is effective when air pressures vary gradually. However, in the case of detonations produced by heavy gunnery, 30 the sound wave is of such great amplitude as to constitute practically a traveling approximately instantaneous violent pressure change in the atmosphere. When this pressure change strikes the external meatus, 35 the Eustachian tube completely fails to maintain the balance in pressure necessary. It is to be noted that gunners, in some instances, at the instant of firing, hold their mouths open in an attempt to facilitate the necessary 40 equalizing in pressure between the aforementioned inner and outer ear cavities. This, however, has not been successful.

It is an object of my invention to provide 45 mechanism which will annul the violent and sudden change of pressure ordinarily to be experienced in the vicinity of the outer ear at the time of the detonation. It is a further object of the invention, while annulling the injurious effect of a concussion, to 50 permit the wearer to hear and perceive sounds of speech amplitude. It is still a further object at the same time preferably to hermetically seal the external meatus.

The above will be better understood by 55 reference to the illustrative embodiments of my invention described in the following

specification in connection with the accompanying drawings, which form a part hereof, and in which like characters designate corresponding parts in the several figures. In the drawings—

Figure 1 is a vertical section, partly in diagram, of a preferred embodiment of my invention, in combination with a human ear;

Fig. 2 is a plan view of the stiffening member embodied in the mechanism of Fig. 1;

Fig. 3 is a fractional section corresponding to Fig. 1, but showing a modification.

Fig. 4 is a view corresponding to Fig. 1, 70 showing a second modification;

Fig. 5 is a diagrammatic representation of my ear protectors as worn by a gunner; and

Fig. 6 is a detail perspective view showing the latch mechanism for the attaching straps.

In the human ear A, shown in Fig. 1, 1 indicates the auricle, 2 the external meatus, 3 the tympanum or ear drum, and 4 the 80 tympanic cavity. In the preferred embodiment of my invention, I shape the apparatus roughly to conform to the outline of the auricle and so as completely to cover the same. 5 is a perforated sheet-metal 85 plate having such desired contour and providing the strap attaching lugs 6 and 7, to which straps 8 and 9 may be secured in any approved manner. Molded about the plate 5 is a pad of vulcanized rubber 10, preferably passing through the perforations 11 and formed into a flat wall 12 on the external side of the structure and into a plug 13 on the opposite side, emerging into a wall 14 roughly approximating the shape of 95 the auricle. This structure, comprising essentially the portion overlying the auricle 1 such as the parts 5 and 10 in Fig. 1, and 10' in Fig. 4, constitute what I term the concussion shield. In the structure of Fig. 1 the plug 13 also serves as a functioning part of such a shield. To the rim of the wall 12 is attached the rim or flange 15 of resilient rubber having one or more small perforations 16 and providing a mounting 17 for a resiliently movable outer wall preferably in the form of a diaphragm 18. The diaphragm 18 is preferably my cusp diaphragm such as has been described in my Patent No. 1,220,669, granted March 27, 110 1917.

The rubber flange 15 is designed so that,

upon a detonation, the diaphragm 18 may yield an appreciable distance inwardly *i. e.*, to the left, as viewed in Fig. 1, which causes air to be expelled from the perforations 16 and dissipates the energy of the violent sound wave or concussion by the work done by collapsing the rubber flange and expelling air through the perforations 16.

In use, a pair of my ear protectors B, C 10 are employed, the strap 8 interlinking the top lugs 6, and the two-part strap 19 interlinking the bottom lugs 7. In the strap 19 I preferably provide a quick-acting latch 20, which coöperates with the bail 21 so that, when in 15 the position shown in Figs. 5 and 6, the straps are tight about the wearer's head, but by pulling up on the latch 20, the latch will pass through the bail 21 until the roll 22 engages the bail. This effects the loosening 20 of the strap so that the ear protectors stand out sufficiently for the receiving of commands.

In Fig. 3 the apparatus to the left of the structure 10 is to be understood as identical 25 with that of the form shown in Fig. 1. In this modification, however, the flange 15' is made of textile fabric and the diaphragm 18 is pressed outwardly by the spiral spring 30. The interstices in the fabric permit the escape 30 of air.

The modification of Fig. 4 comprises a metal box 31, vulcanized to the concussion shield member 10' which has strap attaching lugs 6' and 7'. The walls of this box 35 have perforations 16'. The movable outer wall in the form of the diaphragm 18' is attached by the hinge 32 to the rim of the box opening 33 and is pressed outwardly by the spiral spring 34 stayed by the stem 35.

40 What I claim and what I desire to secure by United States Letters Patent is:—

1. An instrument for protecting the ear against damage by sound concussions comprising a concussion shield of massive, im- 45 perforate, rigid construction for covering substantially the entire auricle; and a re- siliently yieldable outer wall conforming substantially in contour with that of said

shield; and means securing said wall to said shield in an outwardly spaced position and 50 permitting the lateral escape of the air in the space between said wall and said shield when said wall moves in response to a concussion.

2. An instrument for protecting the human ear against damage by sound-concussions comprising, a rigid closure for the external meatus; a rigid barrier for covering the auricle; a movable diaphragm spaced outwardly from said barrier; and a yieldable 60 rim mounting said diaphragm upon said barrier.

3. An instrument for protecting the human ear against damage by sound-concussions comprising, a rigid closure for the external meatus; a rigid barrier for covering the auricle; a movable dished diaphragm spaced outwardly from said barrier; and a yieldable rim mounting said diaphragm 70 upon said barrier.

4. An instrument for protecting the human ear against damage by sound-concussions comprising, a rigid closure for the external meatus; a rigid barrier for covering the auricle; a movable eccentrically dished 75 diaphragm spaced outwardly from said barrier; and a yieldable rim mounting said dia- phragm upon said barrier.

5. An instrument for protecting the ear against damage by sound-concussions comprising an extensive concussion shield of rigid construction covering substantially the entire auricle and external meatus; an inwardly yieldable outer wall overlying, conforming in shape with and spaced apart 85 from said shield; a laterally vented yieldable flange securing said wall to said shield and forming an air space and structure to convert energy from a concussion into harmless work; and means for securing said shield in 90 position about and overlying the auricle in sound sealing relation thereto.

In testimony whereof I have signed my name to this specification, this 25th day of March, 1918.

FRANK E. MILLER.
